THE NORRIS PETERS CO., PHOTO-LITHO., WASHINGTON, D. C.

UNITED STATES PATENT OFFICE.

THOREY I. MOEN, OF CHIPPEWA FALLS, WISCONSIN.

ANIMAL-TRAP.

1,141,815.

Specification of Letters Patent.

Patented June 1, 1915.

Application filed June 9, 1914. Serial No. 844,070.

To all whom it may concern:

Be it known that I, THOREY I. MOEN, a citizen of the United States, residing at Chippewa Falls, in the county of Chippewa and State of Wisconsin, have invented certain new and useful Improvements in Animal-Traps, of which the following is a specification.

The primary object of this invention is to provide a device for entrapping rodents, and similar animals, into a receptacle by means of automatically setting trap doors so arranged that the springing of said doors does not take place until the rodent has advanced over one and onto another of the same, the latter door being operably connected to a trigger, normally maintaining the first mentioned door in inoperative position, so that upon contact of the rodent with the second mentioned door said rodent is suddenly precipitated into the receptacle by the simultaneous yielding of said doors. It is contemplated to employ a guard member associated with the second door and beneath which the bait is disposed, for the purpose of preventing the escape of the rodent by leaping in the direction of its movement onto the doors, when it first feels yielding of the same under its weight. These and such other objects as may hereinafter appear are attained by the novel construction, combination and arrangement of parts to be herein-after specifically described and claimed.

Reference will now be had to the accompanying drawings forming a part of this specification, wherein—

Figure 1 is a perspective view of an embodiment of this invention. Fig. 2 is a longitudinal sectional view through the device. Fig. 3 is a horizontal sectional view on the line 3—3 of Fig. 2 looking in the direction of the arrows. Fig. 4 is a vertical sectional view on the line 4—4 of Fig. 2. Fig. 5 is a vertical sectional view on the line 5—5 of Fig. 2. Fig. 6 is a sectional view on the line 6—6 of Fig. 5, and Fig. 7 is a sectional view on the line 7—7 of Fig. 4 showing more clearly the pivotal mounting of a door employed in this trap.

Throughout the following detail description, and on the several figures of the drawings, similar parts are referred to by like reference characters.

Referring to the drawings and specifically describing the invention, the numeral 1 designates a receptacle, the material of which is preferably metal, said receptacle being provided with a pair of co-operating trap doors 2 and 3 pivotally mounted in an opening in its upper surface as at 2', 3'. As a matter of convenience a gangway 4 is secured to the receptacle at one end so as to enable the rodent to be entrapped to gain access to the upper surface of the receptacle. It will be noted particularly that the mechanism for controlling the operation of the trap doors of this device is disposed within the receptacle and for the purpose of presenting a device in which the moving parts are not likely to arouse the suspicion of a rodent as to the nature of the same. This mechanism will now be described.

Near the forward end of the receptacle 1 of the trap is provided a partition 5 extending transversely of the receptacle and having a vertical slot 5' therein in which is pivotally mounted a trigger 6, the trigger being of a weighted variety so as to automatically cause this element to assume a normal upright position such as is shown in Figs. 2 and 6. The upper end of the trigger is notched and normally engages over a spring loop member 7 pendent from one end of the door 2. Pivotally secured to a wall of the partition 5 is a double arm operating lever 8, one arm 8' of which is secured to the upper end of the trigger 6 as shown at 8''. The other arm 8'' of the lever 8 extends or is bent downwardly from the main portion of said lever and is connected by means of a link or bar 9 to the pendent arm 10' of a second double arm lever 10 pivotally mounted beneath the trap door 3. The second arm 10'' of the lever 10 extends forwardly of the door and contacts therewith as shown most clearly in Figs. 2 and 3. This door is also provided at its rear end with a pendent loop 11 the purpose of which will more clearly be set forth hereinafter.

With the above details of construction in mind the operation of the device will be apparent from the following: The bait for the trap is preferably disposed at the rear end of the receptacle 1 adjacent the rear end of the trap door 3 and beneath a guard member or cage 12 which is disposed upon

the upper surface of the receptacle in a position surrounding this door. When the rodent passes up the gangway 4 onto the surface of the receptacle and advances onto the door 2 toward the bait at the farther end of said receptacle said door is prevented from yielding by reason of the engagement of the trigger 6 with the pendent loop 7 carried by the door 2. Immediately upon the contact of the rodent with the door 3, the rodent's weight will cause the door to yield downwardly at its free end which actuates the lever 10 and through the connection 9 the operating lever 8 will pull the upper engaging extremity of said trigger from engagement with the loop 7, thereby releasing the door 2, and the simultaneous yielding of these trap doors will suddenly precipitate the animal into the receptacle. As will be obvious, said receptacle may contain water or similar liquid so that the rodent will be drowned after it has been dropped thereinto or I may employ in conjunction with the trap electrocuting means by which the rodent will be killed upon the closure of a circuit in which the doors 2 and 3 are included. For this purpose the circuit wires 13 and 14 leading from a source of electrical energy such as a battery (not shown) are connected to the doors 3 and 2 respectively, as most clearly shown in Figs. 2 and 3, the circuit being maintained open by reason of the spacing of the free ends of said doors from each other, or if desired said doors may be suitably insulated from each other in a manner well known to those skilled in this art. To enable the transmission of the electric current the doors are understood to be of metallic material so that when the rodent, standing upon the door 2 moves onto the door 3 the circuit is closed and the electrocution takes place as he is precipitated into the receptacle. The partition 5 is preferably provided adjacent its upper edge with an inwardly projecting arm 15 which by its engagement with the spring loop member 7 limits the pivotal movement of the door 2 as shown in dotted lines of Fig. 2. Likewise the door 3 is limited in its movement by the provision of a projecting abutment arm 16 extending from the partition 17 in said receptacle through the coöperation of said arm with the spring loop 11. As hereinbefore mentioned, the lower end of the trigger 6 is weighted or made heavy in its formation so as to automatically return to its upright position when the doors have been sprung and the weight of the rodent is removed therefrom. This trigger, therefore, acts to forcibly cause the door 3 to assume its original horizontal position. The door 2 is weighted at its outer edge as shown at 18 so that when the weight of the

animal is taken from said door it will descend at this end and the loop 7 which is of a yielding character will engage beneath the hooked terminal of the trigger. It will be apparent that the spring 7 performs a dual function in that it maintains the door in normal horizontal position by its coöperation with the trigger 6 as above described and also acts to limit the pivotal movement of said door through its coöperation with the abutment arm 15. It sometimes occurs that the rodent upon the initial yielding of trap doors in devices of this character effects its escape by leaping therefrom and to guard against this possibility I have employed the guard screen 12 surrounding the door 3, which guard also prevents access to the bait without approaching toward the same over the trap doors.

Having thus described the invention, what is claimed as new is:

1. In a trap of the class described, the combination of a pair of pivoted trap doors, a trigger member pivotally mounted adjacent one of said doors for holding the same against movement, connecting means intermediate the other of said doors and one end of the trigger for moving the latter corresponding with the pivotal movement of the last mentioned door into disengaging and engaging positions with respect to the first mentioned door, and yieldable means on the first mentioned door for springing into engagement with the trigger when the latter is in its normal engaging position.

2. In a trap of the class described, the combination of a pair of pivoted trap doors, a trigger member pivotally mounted beneath one of said doors for holding the same against movement, connecting means intermediate the other of said doors and one end of the trigger for moving the latter corresponding with the pivotal movement of the last mentioned door into disengaging and engaging positions with respect to the first mentioned door, a spring on the first mentioned door for engaging with the trigger when the latter is in its normal engaging position, and stop means engageable by the yieldable means for limiting movement of the first mentioned door.

3. In a trap of the class described, the combination of a receptacle, trap doors pivotally mounted on said receptacle, a weighted trigger pivotally secured adjacent one of said doors and normally disposed in an upright position, a yieldable loop member pendent from said door and engaged by the trigger to normally hold the door against movement, a double arm lever secured to the other of said doors, a link member connected to one of the arms of the aforesaid lever, an operating lever disposed adjacent the trigger and connected thereto at one

end and to the link at its other end whereby upon springing of the trap doors to cause the last mentioned door to resume its normal operative position, and stop members 5 for limiting pivotal movement of the doors when sprung.

In testimony whereof I affix my signature in presence of two witnesses.

THOREY I. MOEN.
